[57] ABSTRACT

A switching jack for use with a circuit board. The switching jack includes a housing having a single opening for receiving a standard plug. Within the housing is a contact carrier which holds a plurality of resilient conductive pins. The resilient conductive pins extend angularly through an open area in the housing and extend out from the rear surface of the jack. When the jack is mounted to a circuit board the resilient conductive pins contact grooved contacts formed in the circuit board. The electrical connections between the resilient conductive pins and the grooved contacts is interrupted when a plug is placed in the jack.

SWITCHING JACK

BACKGROUND OF THE INVENTION

1. Field of the Invention

The invention relates generally to a modular jack and in particular to a modular jack having a single opening for receiving a standard modular plug which, when inserted in the jack, disconnects conductive pins from a circuit board.

2. Prior Art

Modular jack patching devices are known in the art as exhibited by U.S. Pat. No. 5,074,801. Referring to FIG. 1, the '801 patent describes a modular jack patching device having a pair of oppositely disposed openings 2 and 4 for receiving standard modular plugs. A circuit board 6 is clipped to the back side of the housing, as shown in FIG. 2, for establishing an electrical connection between resilient conductive pins 8 positioned in the openings 2 and 4. Resilient conductive pins 8 normally establish an electrical connection with the circuit board 6. When a plug is inserted in the opening 2 or 4, the pins 8 are deflected away from the circuit board 6 and the electrical connection between the resilient conductive pins 8 and the circuit board 6 is broken. U.S. Pat. No. 5,178,554 discloses a similar modular jack patching device.

Although the modular jack patching devices of U.S. Pat. Nos. 5,074,801 and 5,178,554 are well suited for their intended purposes, there are difficulties using these modular jacks in a variety of applications. The size of the dual opening modular jack makes it difficult to use the jack with existing systems. In addition, certain applications only require a single jack in which the dual opening modular jack of the prior art is unnecessary.

SUMMARY OF THE INVENTION

The above-discussed and other drawbacks and deficiencies of the prior art are overcome or alleviated by the switching jack of the present invention. The switching jack of the present invention includes a housing having a single opening for receiving a plug. Within the housing is a contact carrier which holds a plurality of resilient conductive pins. The resilient conductive pins extend angularly through an open area in the housing and extend out from the rear surface of the jack. When the jack is mounted to a circuit board, the resilient conductive pins contact grooved contacts formed in the circuit board. When a plug is inserted in the jack, the electrical connections between the resilient conductive pins and the grooved contacts is interrupted. In an alternative embodiment, the housing includes an opening for receiving an icon.

The housing only has a single opening and thus has a smaller size than prior switching jacks. Accordingly, the switching jack of the present invention can be used in applications not suitable for the larger, dual-opening switching jacks.

The above-discussed and other features and advantages of the present invention will be appreciated and understood by those skilled in the art from the following detailed description and drawings.

BRIEF DESCRIPTION OF THE DRAWINGS

Referring now to the drawings wherein like elements are numbered alike in the several FIGURES:

FIG. 1 is a perspective view of the conventional dual opening modular jack;

FIG. 2 is an alternative perspective view of the conventional dual opening modular jack;

FIG. 3 is an exploded view of the switching jack of the present invention and a circuit board;

FIG. 4 is an alternative exploded view of the switching jack of the present invention and a circuit board;

FIG. 5 is a rear view of the switching jack mounted to a circuit board;

FIG. 6 is a left side view of the switching jack mounted to a circuit board;

FIG. 7 is a top view of the switching jack mounted to a circuit board;

FIG. 8 is a cross sectional view taken along line 8—8 of FIG. 7;

FIG. 9 is a cross sectional view taken along line 9—9 of FIG. 7;

FIG. 10 is a top view of the switching jack;

FIG. 11 is a front view of the switching jack;

FIG. 12 is a right side view of the switching jack;

FIG. 13 is a perspective view of the switching jack with the rear side up;

FIG. 14 is a perspective view of the switching jack with the front side up;

FIG. 15 is a perspective view of the switching jack including an icon;

FIG. 16 is an exploded view of an alternative switching jack;

FIG. 17 is a perspective view of the switching jack of FIG. 16; and

FIG. 18 is a perspective view of the switching jack of FIG. 16.

DETAILED DESCRIPTION OF THE INVENTION

FIG. 3 is an exploded view of the switching jack, made up of housing 10, resilient conductive pins 20 and a contact holder 30, and a circuit board 40. To assemble the switching jack, the conductive pins 20 are first mounted to the contact carrier 30. The rear section 302 of the contact carrier 30 includes a plurality of holes 304 and slots 306 shown in FIG. 4. The rear section 302 forms the rear face of the switching jack when connected to the housing. A first end 202 of each of the conductive pins 20 extends through the holes 304 in the contact carrier 30. A second end 204 of each of the conductive pins 20 extends through the slots 306. A bottom section 308 of the contact carrier 30 includes a front lip 50 having a plurality of notches 310 for receiving a portion of the conductive pins 20. The notches 310 keep the conductive pins 20 separated and maintain the proper separation between the individual conductive pins 20. Although eight conductive pins 20 are shown in FIG. 3, it is understood that pin configurations such as two, four, six, and ten may be used in the switching jack.

Once the conductive pins 20 are mounted to the contact carrier 30, the housing 10 is then snapped on to the contact carrier 30. In an exemplary embodiment, both the contact carrier 30 and the housing 10 are made from a resilient plastic which allows the contact carrier 30 to be connected to the housing 10 without damage to the housing or contact carrier. A pair of tabs 312 formed on the periphery of the bottom section 308 of the contact carrier 30 engage a pair of slots 102 formed in side walls of the housing 10. In addition, two fingers 314, having a recess 316, engage two ribs 104 formed on the inside of the side walls of the housing. The

60

65

ribs **104** are positioned with the recesses **316**. The interference fit between the ribs **104** and the recesses **316** and the tabs **312** and slots **102** connect the contact carrier **30** to the housing **10**. The assembled housing **10**, conductive pins **20** and contact carrier **30** forms the switching jack.

The switching jack is then mounted to a circuit board **40** to form a patching module for performing various operations depending on the specifics of the circuit board **40**. The housing **10** includes a pair of tabs **106** having a neck **108** and a head **110** having a half conical shape. The neck **106** has an outer dimension that is smaller than the base of the head **110**. The circuit board **40** includes holes **402** for receiving the tabs **106**. The lip between the head **110** and the neck **108** engages the circuit board **40**. The interference fit between the head **110** and the circuit board **40** connects the switching jack to the circuit board. The circuit board **40** includes holes **404** that receive the first end **202** of the conductive pins **20**. An elongated aperture **406** is formed in the circuit board **40**. Within the aperture **406** are contact grooves **408** that receive the second end **204** of the conductive pins. The first end **202** of the conductive pins **20** is permanently attached to the circuit board **40** by soldering. The contact between the second end **204** of the conductive pins **20** and the contact grooves **408** is broken when a plug is inserted in an opening **112** formed in the housing **10**. The opening **112** is substantially parallel to the surface of the contact carrier **30** that the first ends **202** extend through.

FIG. 5 is a rear view of the switching jack mounted to the circuit board **40**. The second end **204** of the conductive pins **20** contact the grooved contacts **408** formed in the aperture **406**. FIG. 6 is a left side view of the switching jack connected to the circuit board **40**. FIG. 7 is top view of the switching jack connected to the circuit board **40**. FIG. 8 is a cross sectional view taken along line **8—8** in FIG. 7. FIG. 9 is a cross sectional view taken along line **9—9** of FIG. 7. As shown in FIGS. 8 and 9, the resilient conductive pins **20** extend angularly through an open area in the housing. When a plug is inserted in the opening **112** in housing **10**, the second end **204** of the conductive pins **20** are flexed away from the contact grooves **408** in the aperture **406**. When the plug is removed, the conductive pins **20** return to their original shape and the second ends **204** contact the groove contacts **408** in the aperture **406**. FIG. 10 is a top view of the switching jack. FIG. 11 is a front view of the switching jack. FIG. 12 is a right side view of the switching jack. FIGS. 13 and 14 are perspective views of the switching jack.

Due to its reduced size, the single opening switching jack can be used in applications where the dual opening switching jacks of the prior art cannot be used. In addition, category 5 compliant patching applications can be designed by using two vertical switching jacks and a specific printed circuit board.

FIG. 15 is a perspective view of an alternative housing **10'**. The alternative housing **10'** includes a pocket **50** for receiving an icon **60** which may be used for color coding or keying the jack. The icon **60** includes a projection **62** that is aligned with a notch **52** formed in the periphery of the pocket **50**. The interaction between the projection **62** and the notch **52** ensure that the icon **60** is placed in the pocket **50** in the proper orientation. The icon **60** also includes a pair of bumps **64** that engage recess **54** formed in the interior wall of the pocket **50**. The interference fit between the bumps **64** and the recesses **54** prevent the icon **60** from becoming dislodged from the housing **10'**.

FIG. 16 is an exploded view of an alternative switching jack having an alternative housing opening location. The

alternative switching jack is made up of a housing **50**, resilient conductive pins **60** and a contact carrier **70**. To assemble the switching jack, the conductive pins **60** are first mounted to the contact carrier **70**. The rear section **702** of the contact carrier **70** includes a plurality of slots **706** shown in FIG. 16. The rear section **702** forms the rear face of the switching jack when connected to the housing. A plurality of openings **704** are formed in a bottom section **708**. A first end **602** of each of the conductive pins **70** extends through the openings **704** in the contact carrier **70**. A second end **604** of each of the conductive pins **60** extends through the slots **706**. A bottom section **708** of the contact carrier **70** includes a front lip having a plurality of notches **710** for receiving a portion of the conductive pins **60**. The notches **710** keep the conductive pins **60** separated and maintain the proper separation between the individual conductive pins **60**. Although eight conductive pins **60** are shown in FIG. 16, it is understood that pin configurations such as two, four, six, and ten may be used in the switching jack.

Once the conductive pins **60** are mounted to the contact carrier **70**, the housing **50** is then snapped on to the contact carrier **70**. In an exemplary embodiment, both the contact carrier **70** and the housing **50** are made from a resilient plastic which allows the contact carrier **70** to be connected to the housing **50** without damage to the housing or contact carrier. A pair of tabs **712** formed on the periphery of the bottom section **708** of the contact carrier **70** engage a pair of slots **502** formed in side walls of the housing **50**. In addition, two fingers **714**, having a recess **716**, engage two ribs **504** formed on the inside of the side walls of the housing **50**. The ribs **504** are positioned with the recesses **716**. The interference fit between the ribs **504** and the recesses **716** and the tabs **712** and slots **502** connect the contact carrier **70** to the housing **50**. The assembled housing **50**, conductive pins **60** and contact carrier **70** forms the switching jack.

FIG. 17 is a perspective view of the alternative switching jack mounted to a circuit board **80**. The second end **604** of the conductive pins **60** extend angularly through an open area in the housing. When a plug is inserted in the opening **112** in housing **50**, the second end **604** of the conductive pins **60** are flexed away from the contact grooves **808** in the aperture **806**. When the plug is removed, the conductive pins **60** return to their original shape and the second ends **604** contact the groove contacts **808** in the aperture **806**. FIG. 18 is a top view of the switching jack. FIG. 19 is a front view of the switching jack. FIG. 20 is a right side view of the switching jack. FIGS. 21 and 22 are perspective views of the switching jack.

FIGS. 17 and 18 are perspective views of the alternative switching jack. As described above with reference to FIGS. 8 and 9, the resilient conductive pins **60** extend angularly through an open area in the housing **50**. When a plug is inserted in the housing **50**, the plug presses against the resilient conductive pins **60** and forces the second end **604** out of contact with the contact grooves **808** formed in circuit board **80**.

The single opening switching jack of the present invention provides advantages over the prior art. The compact size of the single opening switching jack allows it to be used in applications where larger, dual-opening switching jacks cannot be used. In addition, the inclusion of an icon holder in the switching jack housing provides for color coding or keying of individual switching jacks.

While preferred embodiments have been shown and described, various modifications and substitutions may be made thereto without departing from the spirit and scope of the invention. Accordingly, it is to be understood that the present invention has been described by way of illustration and not limitation.

What is claimed is:

1. A switching jack comprising:

a housing having a single opening for receiving a plug; a plurality of resilient conductive pins having a first end and a second end, said plurality of resilient conductive pins extending through an open area in said housing such that said second end of said resilient conductive pins moves when the plug is inserted in said housing; and

a contact carrier for receiving said resilient conductive pins and engaging said housing, said contact carrier having a rear section and a bottom section substantially perpendicular said rear section, said rear section being integrally formed with to said bottom section, said first end of said resilient conductive pins extending through holes in said rear section and said second end of said resilient conductive pins extending through slots in said rear section;

5

10

15

20

25

wherein said first end of said resilient conductive pins extends beyond said rear section a distance sufficient to enable said first end to make electrical contact with a circuit board; and

wherein when a plug is not inserted in said housing, said second end of said resilient conductive pins extends beyond said rear section a distance sufficient to enable said second end to make electrical contact with the circuit board.

2. The switching jack of claim 1 wherein said housing further comprises at least one slot formed therein and said contact carrier further comprises at least one tab for engaging said slot when said contact carrier is coupled to said housing.

3. The switching jack of claim 1 wherein said contact carrier further comprises at least one finger including a recess formed in the finger and said housing further comprises a rib for engaging said recess formed in said finger when said contact carrier is coupled to said housing.

4. The switching jack of claim 1 wherein said opening is parallel to said rear surface.

5. The switching jack of claim 1 further comprising tabs extending from said housing for securing said housing to the circuit board.
